FIG. 1 is a front elevational view of a casing for a wall clock, wall plaque or similar article showing my new design, the rear being plain and unornamented;

FIG. 2 is a top plan view thereof, the bottom plan view and side elevational views being substantially similar thereto;

FIG. 3 is a sectional schematic view taken along the line 3-3 of FIG. 1, the internal structural details having been omitted as non-ornamental;

FIG. 4 is a front elevational view of another embodiment of a casing for a wall clock, wall plaque or similar article, the rear being plain and unornamented;

FIG. 5 is a top plan view of the embodiment shown in FIG. 4, the bottom plan view and side elevational views being substantially similar thereto; and

FIG. 6 is a sectional schematic view taken along line 6-6 of FIG. 4, the internal structural details having been omitted as non-ornamental.

I claim:

The ornamental design for a casing for a wall clock, wall plaque or similar article, as shown and described.
